UNITED STATES PATENT OFFICE.

CHARLES J. VAN DEPOELE, OF LYNN, MASSACHUSETTS.

ELECTRIC-RAILWAY SYSTEM.

SPECIFICATION forming part of Letters Patent No. 448,563, dated March 17, 1891.

Application filed December 13, 1890. Serial No. 374,581. (No model.)

To all whom it may concern:

Be it known that I, CHARLES J. VAN DEPOELE, a citizen of the United States, residing at Lynn, in the county of Essex and State of Massachusetts, have invented certain new and useful Improvements in Electric-Railway Systems, of which the following is a description, reference being had to the accompanying drawings, and to the letters and figures 10 of reference marked thereon.

My invention relates to an improved system of propelling cars or trains of cars upon an electric railway, and in general the invention comprises improvements upon the inventions set forth in my prior patents, numbered 15 434,684 and 434,685, dated August 19, 1890.

My prior patents fully set forth the advantages of the system under which the supply-current is received at some point or points 20 upon the train, and there modified and supplied to the local or traveling motor circuit, and the same is true in the present instance. I have, however, in this case, embodied a number 25 of very desirable improvements which will be hereinafter fully set forth and referred to in the appended claims.

As shown in the drawings, the motor or motors are of the type set forth and described in an application filed December 20, 1890, 30 Serial No. 375,308, as well as in other of my pending cases, and while I have described several novel features in connection with such a motor which have decided advantages in practice, those features of the present application 35 which refer to motor regulation are not limited to any particular form or construction of motor.

In the drawings, Figure 1 is a diagrammatic view, partly in elevation, showing parts 40 of an electric-railway motor-car with electrical apparatus embodying the invention; also the supply circuit and connections. Fig. 2 is a view in elevation showing part of an electric-motor car provided with a traveling 45 contact device and electrical apparatus and circuits embodying the invention. Figs. 3 and 4 are views in elevation showing parts of a motor-truck equipped with motors embodying the invention, and further provided 50 with means for reversing the direction of rotation thereof. Fig. 5 is a diagrammatic view,

partly in elevation, showing the relation of the different parts of the system, but differing from Fig. 1 in showing additional means for current regulation. Fig. 6 is a detail view 55 of solenoid and current-controlling switch therefor.

In Fig. 1 of the drawings, A is the bed or frame-work of a car, of which C C' are the carrying-wheels, and B B the propelling-motors, by preference mounted directly upon the axles thereof. The said motors are operated by current received from a dynamo-electric machine D operating as a counter-electro-motive force device and carried in any 60 convenient position upon the car. Current is supplied to the machine D by traveling current-collecting devices—as, for example, the trolley E which is suitably supported upon the vehicle and provided with a contact 65 e at its free end, said contact engaging a main conductor 1—extending along the line of travel.

G indicates a generating-station, from the positive and negative sides of which the current is taken; and 2 is the return-conductor, which in this instance is connected with the rails F of the track upon which the vehicles 70 travel. A double overhead circuit is shown in Fig. 2; but any other disposition of the 75 supply-conductors can be adopted, as desired.

As set forth in my said prior patent, many practical advantages are gained by the method of propulsion upon which this is an improvement; but a special feature of this case is that according to my present invention I employ 80 motors the armature-circuits of which are energized wholly by induction, so that but a single circuit is necessary and that including 85 only the coils of the field-magnets thereof.

An induction-motor of the type here employed is shown and described in my patent, No. 433,834, August 5, 1890, and comprises an armature of the continuous-current type having a finely divided or laminated core and a field-magnet for said armature, also having a core of subdivided iron. The degree of lamination in both instances should depend upon and accord with the nature of the current by 90 which the field-magnet is energized.

In my prior patent the current-modifying

devices carried by the motor-car, and to which the main supply-current is led, are specially designed to modify said current in order to enable me to employ currents of relatively high tension and to distribute currents of relatively low tension to the train-circuit, and this arrangement might be employed in the present instance in connection with certain of the improvements herein contained; but I 5 find that extremely good results are produced by a form of apparatus which serves merely to change the character of the current without affecting its potential. To this end the counter-electro-motive-force device or converter D is an ordinary electro-dynamic machine of the continuous-current type which receives the supply-current and distributes current of alternating polarity. This result is secured by providing the armature H of the 10 machine D with two insulated rings h' h^2 in addition to the regular sectional commutator h . The said rings are each connected with a diametrically-opposite section of the commutator h , so that during the rotation of the 15 armature H the sections connected to said rings will pass alternately between the positive and negative poles of the machine, and therefore contact devices placed upon said rings will transmit alternately positive and 20 negative impulses.

As shown in Fig. 1, the machine D is mounted in convenient position upon the car and is in direct connection with the trolley by conductor 3, which extends to the hand-lever I of a rheostat i , from the other extremity of which the current passes by conductor 4 to the field-magnet coils d' of the machine D. From the other extremity of the field-magnet coils d' the current passes to the main positive 25 stationary commutator-brush P, passing thence into the armature and issuing by an oppositely-placed brush n , and from there by conductor 5 to the rails F, or whatever form of return-circuit may be provided. The 30 brushes P N are the ordinary commutator-brushes of a continuous-current machine and are adjustably sustained in any desired manner.

The distributor D is operated as a series 35 motor, and the resistance i is employed to regulate the speed thereof, and therefore the rate of the phase of the alternating currents supplied to the field-magnets of the motors. In connection with resistance i , I provide, 40 however, an additional contact i' , which is in the path of the switch-lever I after the same has passed from a suitable portion of the resistance. Upon reaching the contact i' the 45 connections are changed so that the remaining portion of the resistance is put in multiple arc with the field-magnet coils of the machine D and part of the current is shunted around them, passing directly to the armature. This will operate to diminish the speed 50 of the machine D and the rate of phase.

Upon the axles $C^2 C^3$ of the carrying-wheels are mounted motor-armatures J. The said

armatures may be of the continuous-current type, each provided with the usual sectional commutator j ; but this may be modified by 55 winding the armature-coils in sections corresponding in number with the magnet-poles, the terminals of each section being connected to a separate commutator-segment and commutator-brushes corresponding in number to the circuits to be closed. Brush-holders K are provided for each commutator, said brush-holders carrying equidistant brushes corresponding in number and relationship to the field-magnet poles by which the armature is 60 operated. Exterior to the armatures J are field-magnets L, cylindrical in form, and although they may of course be wound with one continuous wire coil, as a Gramme ring, and having consequent poles, I have here shown them 65 as having four polar extensions l' l^2 l^3 l^4 , the said pole-pieces being united by iron cores l , wound with magnetizing-conductor M. All 70 four of the field-magnet coils M are connected in series. The commutator-brushes are all 75 united, so as to short-circuit the armature at different points, and thereby to localize the poles set up in said armature by the currents induced therein due to the action of the 80 field-magnets thereon. Contact-brushes are 85 placed upon the rings h' h^2 of the machine D and connected by conductors 67 with the terminals of the field-magnet coils M, and as the 90 armature H revolves with each revolution thereof current impulses will be caused to rise 95 and fall in the said field-magnet coils, the 100 succeeding pulsations being of alternating polarity. The alternating current in the field-magnets reacting upon the armature will produce induced currents therein, which, being 105 short-circuited by the connections between the commutator-brushes, will create poles at the points engaged by the brushes, and said 110 points being suitably arranged with reference to the poles of the field-magnets will cause 115 rotation of the armature in either direction, as desired.

The direction of rotation of the armatures can be controlled by hand or electrically, and in Figs. 3 and 4 I have shown both means in 120 their simplest form.

Fig. 3 shows hand means for control, and Fig. 4 electro-magnetic means, and this latter would be preferable, of course, where a number of motors were to be run from a single point, as where a train of cars all equipped with motors of this type were to be operated from a single distributor D.

As indicated in Figs. 3 and 4, the motor-armatures J are mounted upon the axles $C^2 C^3$ of the carrying-wheels and their field-magnets L are sustained in concentric relation therewith, said field-magnets being contained within a suitable exterior casing, which casing is sleeved upon the axle beyond the extremities 130 of the armatures, that part of the construction being, for instance, similar to what is shown and described in my concurrent application, and no more particular form is here

shown, since the present invention is not limited in its application to motors of any particular mechanical form or structure. As indicated, however, the field-magnets are prevented from rotation by connecting-bars M' , which are securely attached thereto, and when said field-magnets are suitably mounted upon the axle will prevent their rotation. At the same time the bars M' should have some flexibility, so as to allow slight oscillation of the said field-magnets at starting or stopping for the purpose of diminishing the suddenness of said movements.

Each motor-commutator j is of the ordinary sectional type and is provided with an adjustably-mounted and insulated brush-carrying yoke O , which in the present instance is of metal and provided with four equidistant commutator-brushes $q' q^2 q^3 q^4$, properly spring-controlled, bearing upon the commutator at equidistant points, and all in electrical connection through the yoke O . As before stated, the number of brushes should correspond with the number of poles of the field-magnet. As indicated in Fig. 3, the yokes $O O$ are connected by rods $m m'$, insulated therefrom, of course, and said rods are connected to a hand-lever Q , which is provided with a spring-latch q , engaging a segmental rack Q' . The lever Q is suitably mounted at Q^2 , and may be moved back and forth, thereby moving all the brushes upon the two commutators and said lever, together with the brushes, will be held in any desired position by engagement of the spring-latch q with the rack Q' .

In Fig. 4 the yokes O are the same, but they are operated by two connecting-rods joined by an iron plunger R , which is arranged to move within a pair of solenoids $r r'$. The solenoids receive current from the supply-circuit through a suitable switch, and the current may be caused to flow continuously through one or the other, in accordance with which the plunger R will be positioned together with the brushes upon the commutator. The solenoids may be sectional, as shown in Fig. 6, the sections being connected to separate insulated sections $q^5 q^6 q^7 q^8 q^9 q^{10} q^{11} q^{12} q^{13}$ of a switch R' , and by means of which the solenoids as a whole can be weakened at any point by the brush or contact r^{11} , which has an extended surface capable of engaging two or more sections at once. The central section q^7 is of the same length as the face of the contact to allow the current to be sent through either half of the solenoid when desired.

A special feature of improvement is found in the control of the motive power by means of the commutator-brushes. Since the armatures J are energized wholly by induction, and the winding of said armatures is continuous, and since the brushes upon the commutator are electrically connected, the polar points will correspond with the positions of the brushes, the most effective of which is just in the rear of the strongest points of the field-magnet poles. It therefore follows that

the speed and power of the motors may be regulated by simply moving the brushes toward or away from their most effective positions. Furthermore the motors may be deprived of all power without stopping the current by positioning the brushes opposite to the central points of the field-magnets when no induction will take place in the armature. This arrangement will be found very convenient in any instance where frequent short stoppages are to be made, and the consumption of current will not be great during these intervals, since the counter-electro-motive force of the field-magnet coils will operate to check the flow of current therethrough. I find, furthermore, that by the present means an easily-handled and effective method of operation is produced, since the car can be slowed down, stopped, backed, or braked by simply changing the position of the brushes in accordance with the principles above set forth.

As previously stated, I may prefer to employ, in addition to a distributor, means for modifying the electro-motive force of the supply-current, so as to reduce the tension of the currents going to the motor-circuit. An arrangement embodying this principle is shown in Fig. 5, in which $E E' e e'$ are the positive and negative traveling contact devices engaging the line-conductors $1 2$. D' is a counter-electro-motive-force device. S is the distributor or means for converting a continuous current into currents of alternating polarity. T is a motor for operating the moving part of the distributor S . A regulator t is provided for the motor T . $S 9$ are the conductors of the local circuit between the motors $B B B B$, which may be upon two separate cars or upon all four of the axles of a double truck-car, such as is indicated in Fig. 2. $L L L L$ are the field-magnets of the motors, of which $J J J J$ are the armatures. With this arrangement, the current entering through trolley E passes by conductor 10 to the main positive commutator-brush p of the electro-dynamic machine D' , and also passes to the field-magnet coils of the machine T , passing therethrough in series relation to the armature. The other commutator-brush n is connected to the return-conductor 11 , which connects with the trolley E' , connected with the return side of the main circuit. The other terminal of the field-magnet coils is also connected with the return-circuit. The machine D' is provided with a sectional commutator j , and has in addition thereto an insulated ring d^2 , upon which bears a stationary contact d^3 , connected to conductor 12 . Current of continuous direction and of any desired potential is transmitted from the commutator j of the machine D' to the ring d^2 , and thence through contact d^3 and conductor 12 by means of a pair of adjustable auxiliary commutator-brushes $k k$, which engage both the commutator and the ring b^2 . The brushes $k k$ are carried by flexible or

jointed arms $k' k'$, which are connected to a suitable hand-lever k^2 , so that as said lever is moved toward or away from the commutator of the machine D' the brushes will 5 separate and move around said commutator, spanning a greater or less number of the segments thereof, so that the current flowing in the conductor 12 will be of a potential determined by the number of sections between the 10 brushes $k k$. The distributor S might be a machine similar to the distributor D of Fig. 1; but I find that a suitable number of electro-chemical elements constitute a very desirable device for this purpose. The distributor S comprises a group of electro-chemical elements s , which are connected in one series arranged for convenience of illustration in a circle, and these elements are each connected by a conductor s' to an insulated segment of 15 a sectional commutator U . A brush-holder V , carrying commutator-brushes $p' n'$, is mounted in position to be rotated about said commutator, and is further provided with two insulated contact-rings $p^2 n^2$, the ring p^2 being electrically connected with the brush p' , and the ring n^2 with the brush n' , and the 20 said rings are connected through suitable contact-brushes and conductors 13 and 14 with the local circuit 8 9. The conductor 12, extending from the machine D' , is connected with one of the segments of the commutator U , and the opposite segment of said commutator is connected by conductor 15 with the 25 return-circuit through the trolley E' . The motor T , as here shown, is connected in series, receiving current from conductor 16 and positive trolley E , and being connected by conductor 17 with the return-circuit through trolley E' . A regulator t , arranged to vary 30 the strength of the field-magnet of the motor T , provides the desired speed-regulation therefor. From the axis of the armature of the motor t extends a belt T' or other suitable mechanical connection, which, engaging a pulley upon the axis of the brush-carrying arm V , will rotate the same and carry the brushes around upon the commutator U continuously and at the desired speed. It will be understood, 35 therefore, that the supply-current is modified to any desired extent by passing through the machine D' , and thence by conductor 12 to the chemical counter-electro-motive-force device S . Further, that the motor T continuously rotates the brush-carrying arm V upon the 40 commutator of the distributor S , and that with the rotation of said arm currents of alternating polarity are transmitted from the device S to the conductors 8 9, which are connected to the terminals of the field-magnets 45 of the motors B . By varying the position of the brushes $k k$ on the machine D' the potential of the current supplied to the distributor S may be varied as desired, and by increasing or decreasing the speed of the motor T 50 the rate of phase of the alternating currents supplied to the field-magnets of the motors will be varied as desired, thus providing a

most complete and efficient system of regulation.

The motors B are controlled as to their 70 power, direction, rotation, and speed, as has been already set forth.

What I claim as new, and desire to secure by Letters Patent, is—

1. A train system comprising a continuous-current supply-circuit along the line of way, a vehicle or vehicles, a motor or motors arranged to propel said vehicles and comprising a field-magnet and an armature having a sectional winding and commutators therefor and 80 short-circuiting brushes thereon adjustable with relation to the inducing-poles of the field-magnet to control the power and direction of rotation of the armature, a distributor receiving the continuous supply-current and 85 converting the same into currents of alternating polarity, and connections between the distributor and the field-magnets of the motors.

2. A train system comprising a continuous supply-circuit along the line of way, a vehicle or vehicles, motors arranged to propel said vehicles and comprising short-circuited armatures having adjustable commutator-brushes, a distributor receiving the continuous supply-current and converting the same 90 into currents of alternating polarity, connections between the distributor and the field-magnets of the motors, and means for controlling the speed of the distributor, and thereby the rate of phase of the currents sent 95 to the field-magnet coils of the motors.

3. In an electric-railway train system, the combination, with a source of continuous current, of an electro-dynamic machine or distributor receiving said currents and transmitting 105 alternating currents, a motor or motors the field-magnets of which are in circuit with the alternating currents of the distributor and having armatures the winding of which is short-circuited through adjustable commutator-brushes, and means for controlling the 110 inductional effects of the field-magnet upon the armature by varying the positions of said brushes with relation to the poles of the field-magnets of the motors.

4. A system of electric railways comprising a motor-circuit traveling with the vehicles to be propelled, motors connected to the driving-wheels of the vehicles, each having a field-magnet energized by a single alternating or pulsating current, an armature having a continuous winding connected to a sectional commutator, and brushes upon said commutator short-circuiting the sections of the armature corresponding to the effective 120 poles of the field-magnets.

5. In an electric-railway system, a continuous supply-current, a counter-electro-motive-force device or distributor for changing the continuous current into a single alternating 130 current, motors having field-magnets energized by the alternating current, and armatures placed in inductive relation thereto, and means for closing upon themselves and

short-circuiting the sections of the armature-winding corresponding to the inducing-poles of the field-magnets, substantially as described.

5 6. In an electric-railway system, an electric motor consisting of two elements carried by the axles of the vehicles to be driven, said elements each comprising an iron core having more or less finely-divided laminations 10 and coils placed thereon, which under the influence of an alternating or pulsating current produces a number of rising and falling magnetic poles in said field-magnets, and an armature having a sectional winding and a 15 commutator therefor, and means for closing the corresponding sections of the armature upon themselves while rotating with regard to the inducing-poles of the field-magnets.

7. In a train system having one or more 20 motors adapted to propel a vehicle, a source of continuous current extending along the line of way, means for converting the continuous into alternating currents, connections between the source of alternating currents 25 and the field-magnets of the motors, said motors having armatures of the continuous-current type with adjustable electrically-connected commutator-brushes corresponding in number with the poles of their field-magnets, 30 and means for controlling the speed, power, and direction of rotation of the motor-armatures by adjusting the commutator-brushes with relation to the points of induction.

8. In an electric train system, the combination of a vehicle, a source of continuous current extending along the line of way, a motor upon and arranged to propel said vehicle, said motor comprising a closed circuited armature with adjustable electrically-connected brushes and a separate field-magnet circuit, 35 means for converting the supply-current into single currents of alternating polarity and transmitting the phases thereof to the field-magnet coils, and means also for controlling the speed and power of the motor by varying 40 the rate and strength of the currents supplied to the field-magnet coils of the motors.

9. In a railway train system, the combination of a source of continuous current, motors having armatures with commutated windings and commutator-brushes short-circuiting the desired parts of said armature-windings, independent field-magnets, a distributor giving currents of alternating polarity and connected with the terminals of the field-magnets, 50 and a current-modifying device receiving the supply-current and transmitting continuous current at any desired potential from the working conductors to the distributor.

In testimony whereof I affix my signature in 60 presence of two witnesses.

CHARLES J. VAN DEPOELE.
